DESIGN FOR A CAR STOP OR SIMILAR DEVICE

Ernest T. Frisk, Hibbing, and George R. Whittington, Taconite, Minn.

Application June 26, 1941, Serial No. 101,697

Term of patent 14 years

To all whom it may concern:

Be it known that we, Ernest T. Frisk, a citizen of the United States, residing at Hibbing, in the county of St. Louis and State of Minnesota, and George R. Whittington, a citizen of the United States, residing in Taconite, in the county of Itasca and State of Minnesota, have invented a new, original, and ornamental Design for a Car Stop, or Similar Device, of which the following is a specification, reference being had to the accompanying drawing, forming part thereof.

In the drawing:

Figure 1 is a perspective view of a car stop, or similar device, showing our new design.

Figure 2 is a cross sectional view taken through line 2—2 of Figure 1.

The opposite side of the device is substantially similar to that shown in Fig. 1.

We claim:

The ornamental design for a car stop, or similar device, as shown and described.

ERNEST T. FRISK.
GEORGE R. WHITTINGTON.
